2 Sheets-Sheet 2

UNITED STATES PATENT OFFICE.

WIGGERT LANGERAK, OF PELLA, IOWA, ASSIGNOR OF ONE-HALF TO MEYER LANGERAK,
OF PELLA, IOWA.

GRAIN WEIGHER.

Application filed April 17, 1924. Serial No. 707,095.

The object of my invention is to provide an automatic grain weigher of simple, durable and comparatively inexpensive construction.

More particularly, my invention relates to a grain weigher adapted to receive grain discharged from a threshing machine and to weigh the same, and then discharge the weighed grain into any suitable elevator or conveyor.

Still a further object is to provide a weigher rotor having a number of pockets therein which are arranged to register with an inlet and a discharge opening and capable of movement from the inlet opening to the discharge opening, when a predetermined amount of grain is received in one of the pockets in the rotor.

Still a further object is to provide a stop member for retaining the rotor in proper position with a pocket registering with the inlet opening, which stop member is rendered ineffective when a predetermined amount of grain is received within the pocket of the rotor.

Still a further object is to provide positive means for insuring the rotor to be moved to position where it will coact with a stop for permitting its movement.

Still a further object is to provide a scale member capable of being adjusted for varying the time when the rotor will move from one position to another.

Still a further object is to provide a spring actuated pawl for preventing the rotor from moving in one direction.

With these and other objects in view, my invention consists in the construction, arrangement and combination of the various parts of my device, whereby the objects contemplated are attained as hereinafter more fully set forth, pointed out in my claims, and illustrated in the accompanying drawings, in which:

Figure 1 is a front elevation of my improved automatic grain weigher, showing grain elevators connected thereto.

Figure 2 is a sectional view through the casing of the weigher with the rotor and weigher shown in front elevation, the section being taken on line 2-2 of Figure 3.

Figure 3 is a sectional view taken on line

3-3 of Figure 2 showing a top plan view of the rotor and the weigher frame.

Figure 4 is a vertical, central, sectional view taken on line 4-4 of Figure 3.

Figure 5 is a detail, sectional view taken on line 5-5 of Figure 2 showing the stop for retaining the rotor in position to receive the grain; and

Figure 6 is a detail, sectional view taken on line 6-6 of Figure 3 showing the bearings for the rotor and the weigher frame.

In the accompanying drawings, I have used the reference numeral 10 to indicate generally an ordinary grain elevator used in connection with the receiving of grain from a grain auger 11 on an ordinary threshing machine.

The elevator 10 elevates the grain up and discharges it into a chute 12.

My improved weigher comprises a casing 13 having a hinged door 14 on its front side. A closure member 15 is provided for retaining the door 14 in closed position.

Mounted within the casing 13 is a rectangular frame which includes a pair of sides 16 and 17 and a bottom and top 18 and 19. The rectangular frame just referred to is secured to the casing 13 on its top, bottom and one side by means of the rivets 20.

Secured to the sides 16 and 17 of the supporting frame are the brackets 21. The brackets 21 are each provided with a ball bearing race 22 in which are journalled short shafts 23.

A weigher frame 24 which is rectangular in outline is fixed to the short shafts 23 so that the shafts 23 support the weigher frame 24 and permit rotating movement of the weigher frame.

In order to limit the amount of rotating movement of the weigher frame 24, I provide a pair of brackets 25 which are mounted on the sides 16 and 17 of the supporting frame.

The brackets 25 are widened somewhat at their outer free ends and have inturned flanges 26 on their top and bottom ends, which are adapted to have the weigher frame strike thereagainst, thereby limiting the amount of pivotal movement of the weigher frame 24.

Mounted in two of the sides of the weigher

frame 24 are the ball bearing races 27 in which is journalled a shaft 28. One end of the shaft 28 extends through a slot 29 formed in the side 16 of the supporting frame. The purpose of the slot 29 will be hereinafter more fully set forth.

Mounted upon the shaft 28 is a weigher rotor A consisting of a pair of spaced disks 30 arranged with a number of partitions 31 secured thereto by flanges 32 having rivets 33 extending therethrough for connecting the partitions 31 to the disks 30.

It will be noted that the outer ends of the partitions 31 are inclined, as at 34, for forming from each partition a complete pocket. In the drawings, I have shown the weigher rotor provided with four pockets referred to by the reference character B. The weigher rotor A is capable of rotation relative to the weigher frame 24.

From the construction of the parts just described, it will be noted that the weigher frame is mounted upon the supporting frame in the brackets 21 and that the weigher rotor A is rotatably mounted within the bearings formed in the weigher frame 24.

The axis of the weigher frame and the axis of the weigher rotor are spaced somewhat apart, as clearly shown in Figure 2 of the drawings.

The chute 12 extends into the casing 13 through an opening 35 formed in the upper side of the casing. The chute 12 is designed to convey grain into the pockets B formed in the weigher rotor A.

The underside of the casing 13 is provided with an inclined portion 36 which forms a discharge opening 37 for the casing to which may be secured an elevator 38. The elevator 38 is in turn connected to any suitable trough 39 wherein the grain discharged into the trough 39 may be emptied into any suitable container or wagon.

Mounted on each of the disks 30 of the weigher rotor A are a number of outwardly projecting lugs 40, which are so arranged that a set of lugs are so arranged that the corresponding ones on each of the disks 30 are designed to engage a stop for limiting the movement of the rotor A. The lugs are so arranged as to cooperate with one particular pocket B for retaining the pocket in proper position to receive grain discharged from the chute 12.

In order to retain the rotor A in position, I mount a pair of rods 41 in the sides 16 and 17 of the supporting frame, which rods have nuts 42 on one of their ends and a bearing head 43 on the other ends.

A coil spring 44 is mounted on each of the rods 41 and is received between one of the surfaces of the sides 16 and 17 and the nuts 42 on the rods 41, as clearly shown in Figure 5 of the drawings.

A shaft 45 is mounted within the bearing heads 43 and has a roller 46 mounted thereon.

The lugs 40 are adapted to strike against the roller 46 and any abrupt striking or shock will be taken up by the springs 44, which serve as a shock absorber.

From the construction of the parts just described, it will be seen that it is necessary in order to rotate the rotor A, to disengage the lugs 40 from the roller 46.

In order to balance the weigher rotor A and the weigher frame 24, I provide a weight 47 and in order to weigh a predetermined amount of grain within any one of the pockets B, I provide a scale member 48 having a movable weight 49 thereon.

The scale member 48 and the weight 49 can be adjusted to indicate the amount of weight of grain permitted to enter each pocket B. As the grain discharged into the pocket B adjacent the chute 12 reaches a predetermined weight, then the weigher frame 24, which carries the rotor A, begins to rotate upon the short shafts 23, as an axis, thereby carrying the rotor A downwardly to the position shown in dotted lines in Figure 2 of the drawings at which time the lugs 40 will no longer be retained by the roller 46, and then the weight of the grain within the pocket B will cause the rotor A to rotate on its own axis, which is the shaft 28, for permitting the grain to be discharged through the discharge opening 37.

As one pocket is moved to discharge position, the next adjacent pocket is brought into position where it can be filled up.

The rotor A rotates in the direction indicated by the arrow 47^a.

The weigher frame 24 is permitted to move from the solid line position in Figure 2 to the dotted line position shown in Figure 2.

In order to prevent the rotor from any backward movement, that is, in the direction opposite from the direction indicated by the arrow 47^a when one set of the lugs 40 strike the roller 46, I provide a pair of spring actuated pawls 50.

The spring actuated pawls 50 are mounted upon a shaft 51 which is journalled in a pair of bracket arms 52 secured to the casing 13.

A pair of coil springs 53 are wound around the shaft 51 and have one end anchored around the bracket arms 52 and the other ends around the pawls 50.

The lugs 40 are permitted to pass beyond the pawls 50, as shown in Figure 4 of the drawings and the pawls 50 will then project in the path of any rearward movement of the rotor A.

In order to count the number of pockets with grain discharged therefrom, I provide a counter mechanism 54 which is mounted

on the door 15. The counter mechanism is of any suitable kind and has a trip wheel 55 thereon which coacts with a disk 56 on one end of the shaft 28, which disk has a number 5 of pins 57 thereon.

Each time a pocket B is discharged it causes one of the pins 57 to turn the trip wheel 55, which in turn operates the counter 54.

10 A number of side openings 58 are provided in the door 14 of the casing 13 wherein the numbers on the counter may be seen.

15 The slot 29 formed in the side 16 permits the shaft 28 to extend therethrough so that the disk 56 may be secured thereon. The slot 29 permits the up and down movement of the rotor for permitting the lugs 40 to disengage from the roller 46.

20 The door 14 may be opened for adjusting the scale member and the weight 49 for varying the amount of weight permitted to enter each pocket before the weigher rotor operates.

25 In order to insure the weigher rotor A to be raised so that the lugs 40 strike against the roller 46, I provide a cam member 58, against which the lugs must pass when the rotor A is rotated, thus insuring the rotor A to be raised sufficiently for the upper set 30 of lugs 40 to engage the roller 46.

The cam 58 provides a pair of means for raising the rotor A and insuring the same to be stopped at the proper place.

35 Some changes may be made in the construction and arrangement of the various parts of my invention, without departing from the real spirit and purpose of my invention and it is my intention to cover by my claims, any modified forms of structure 40 or use of mechanical equivalents, which may be reasonably included within their scope.

I claim as my invention:

1. An automatic weigher comprising a casing having an inlet and a discharge opening therein a weigher rotor journaled therein, said weigher rotor having a number of pockets therein adapted to register with the inlet and discharge openings in said casing, means for retaining the weigher rotor in 50 position where a pocket registers with the inlet opening and a pocket with the discharge opening, said last means being rendered inoperative when the contents of one pocket reach a predetermined weight for permitting the pocket registering with the inlet opening to move to position where it registers with the discharge opening, lugs on said rotor and a cam arranged in said casing for engaging the lugs on the rotor and causing said weigher rotor retaining means operative immediately before a pocket registers with said inlet opening.

2. An automatic weigher comprising a casing having an inlet and a discharge opening therein, a weigher rotor journaled there-

in, said weigher rotor having a number of pockets therein adapted to register with the inlet and discharge openings in said casing, means for retaining the weigher rotor in position where a pocket registers with the inlet opening and a pocket with the discharge opening, said last means comprising lugs on said rotor, a rotor resiliently mounted in said casing and arranged in the path of rotation of the lugs on the rotor, said means being rendered inoperative when the contents of one pocket reach a predetermined weight for permitting the pocket registering with the inlet opening to move to position where it registers with the discharge opening, means for varying the time when said last means is rendered inoperative, and a cam supported on said supporting frame and positioned to engage said lugs on the said weigher rotor for the purpose of rendering said weigher rotor retaining means operative prior to registry of a pocket with said inlet opening.

3. An automatic weigher comprising a casing, a frame in said casing, said casing having an inlet and a discharge opening, a weigher frame a weigher rotor mounted on said weigher frame, said weigher rotor having a number of pockets therein adapted to register with the inlet and discharge openings in said casing, means for retaining the weigher rotor in position where a pocket registers with the inlet opening and a pocket with the discharge opening, said last means including a stop roller resiliently mounted on said frame, a lug on said weigher rotor for each pocket therein adapted to coact with said stop roller and means for permitting one lug at a time to pass said stop when the contents of the pocket corresponding to its lugs reach a predetermined weight and a cam secured in said casing for preventing one lug at a time passing said stop when a pocket registers with said inlet opening.

4. An automatic weigher comprising a casing, a frame in said casing, said casing having an inlet and a discharge opening, a weigher frame, a weigher rotor mounted on said weigher frame, said weigher rotor having a number of pockets therein adapted to register with the inlet and discharge openings in said casing, means for retaining the weigher rotor in position where a pocket registers with the inlet opening and a pocket with the discharge opening, said last means including a stop member on said frame, said stop being yieldably connected to said frame, a lug on said weigher rotor for each pocket therein adapted to coact with said stop, means for permitting one lug at a time to pass said stop when the contents of the pocket corresponding to its lug reaches a predetermined weight and a cam for engaging one of said lugs immediately before an

other of said lugs reaches said stop for the purpose of insuring engagement of said last mentioned lug with said stop.

5. An automatic weigher comprising a casing having an inlet and a discharge opening therein, a weigher rotor journaled therein, said weigher rotor having a number of pockets therein adapted to register with the inlet and discharge openings in 10 said casing, means for retaining the weigher rotor in position where a pocket registers with the inlet opening and a pocket with the discharge opening, said last means being rendered inoperative when the contents of 15 one pocket reach a predetermined weight, for permitting the pocket registering with the inlet opening to move to position where it registers with the discharge opening, a cam for engaging one of said 20 lugs immediately before it reaches said stop for the purpose of insuring engagement of said lug with said stop and means for preventing the rotor from moving in one direction.
- 25 6. An automatic weigher comprising a casing having an inlet and a discharge opening therein, a weigher rotor journaled therein, said weigher rotor having a number of pockets therein adapted to register 30 with the inlet and discharge openings in said casing, means for retaining the weigher rotor in position where a pocket registers with the inlet openings in said casing, means for retaining the weigher rotor in 35 position where a pocket registers with the inlet opening and a pocket with the discharge opening, said last means being rendered inoperative when the contents of one 40 pocket reaches a predetermined weight for permitting the pocket registering with the inlet opening to move to position where it registers with the discharge opening, and positive means for insuring said last means to operate after each time it is rendered in- 45 operative, said means comprising a cam for

moving said weigher rotor, thereby rendering said weigher rotor retaining means operative.

7. An automatic weigher comprising a supporting frame, a weigher frame mounted 50 thereon, a weigher rotor mounted on said weigher frame, and means for retaining the weigher rotor against rotation until the contents thereof reach a predetermined weight, said means comprising a roller resiliently mounted on said supporting frame in the path of rotation of lugs on said weigher rotor and means for returning the weigher rotor to starting position after it has rotated. 60

8. An automatic weigher comprising a casing having an inlet and a discharge opening therein, a weigher rotor journaled therein, said weigher rotor having a number of pockets therein adapted to register with the inlet and discharge openings in said casing, means for retaining the weigher rotor in position where a pocket registers with the inlet opening and a pocket with the discharge opening, said last means being rendered inoperative when the contents of one pocket reaches a predetermined weight for permitting the pocket registering with the inlet opening to move to position where it registers with the discharge opening, a cam for rendering said weigher rotor retaining means operative immediately before one of said pockets reaches said inlet opening and a counter actuated upon the movement of the pockets from one position to another. 70

9. An automatic weigher comprising a casing, a weigher rotor therein, lugs on said weigher rotor and a resiliently mounted roller in the path of rotation of said lugs for engaging them one at a time and thereby stopping the rotation of said weigher rotor. 85

Des Moines, Iowa, April 10, 1924.

WIGGERT LANGERAK.
